US00D888702S

(12) **United States Design Patent** (10) **Patent No.:** **US D888,702 S**
(45) **Date of Patent:** **** Jun. 30, 2020**

(54) **WIRELESS BATTERY CASE FOR
ELECTRONIC COMMUNICATIONS DEVICE**

(71) Applicant: **SPIGEN KOREA CO., LTD.**, Seoul (KR)

(72) Inventor: **Tae Sung Yoon**, Seoul (KR)

(73) Assignee: **Spigen Korea CO., LTD.**, Seoul (KR)

(**) Term: **15 Years**

(21) Appl. No.: **29/695,669**

(22) Filed: **Jun. 20, 2019**

(51) LOC (12) Cl. **14-03**
(52) U.S. Cl.

USPC **D14/250**

(57) **CLAIM**

The ornamental design for a wireless battery case for electronic communications device, as shown and described.

DESCRIPTION

FIG. 1 is a front perspective view of the wireless battery case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines throughout the drawing figures depict portions of the wireless battery case for electronic communications device that form no part of the claimed design.

1 Claim, 8 Drawing Sheets
